UNITED STATES PATENT OFFICE

KENNETH E. BEMIS, OF GLENDALE, CALIFORNIA

DESIGN FOR A STORE FRONT

Application filed June 20, 1932. Serial No. 44,145. Term of patent 14 years.

To all whom it may concern:

Be it known that I, KENNETH E. BEMIS, a citizen of the United States, residing at Glendale, in the county of Los Angeles and State of California, have invented a new, original, and ornamental Design for Store Fronts, of which the following is a specification, reference being had to the accompanying drawing, forming part thereof.

Fig. 1 shows my new design of store front in perspective. Fig. 2 is a diagrammatic plan view of the store front drawn to a reduced scale.

I claim:

The ornamental design for a store front as shown.

KENNETH E. BEMIS.
